UNITED STATES PATENT OFFICE.

ANTHONY DIXON BROGAN AND ANDREW MURRAY MALLOCII, OF GLASGOW,
SCOTLAND.

DESIGN FOR THE SURFACE ORNAMENTATION OF GLASS.

SPECIFICATION forming part of Design No. 27,446, dated July 27, 1897.

Application filed May 10, 1897. Serial No. 635,945. Term of patent 14 years.

To all whom it may concern:

Be it known that we, ANTHONY DIXON BROGAN and ANDREW MURRAY MALLOCII, citizens of the United Kingdom of Great Britain and Ireland, residing at Firhill, Glasgow, in the county of Lanark, Scotland, have invented and produced a new and original Design for the Surface Ornamentation of Glass, of which the following is a specification, reference being had to the accompanying drawing, forming part thereof.

The design is applied to the surface of glass, and is represented in the accompanying drawing, which shows a plan view.

15 The leading or characteristic feature resides in the unitary design, as shown; and it consists of a series of circular figures or rosettes *a*, arranged in diagonal rows and whose boundary-lines touch or nearly touch each other, 20 the boundary of each figure being formed by the outer base of a circular ridge *b*. From the inner base of the circular ridge a series of prismatic or pyramidal ridges *c* converge

radially to the center of each figure. The spaces between the circular figures are filled by prismatic or pyramidal ridges *d*, radiating from the center of each space toward the boundaries of the circular figures. The black shading on the drawing represents one side or face of each prismatic or pyramidal ridge 25 and the white portion the other side or face, the end facets *e* being shown white. The circular ridge around each rosette is not shaded, but its upper edge is shown by the line *f* and the outer and inner bases by separate lines. 30

We claim—

The design for the surface ornamentation of glass substantially as herein shown and described.

Signed at Glasgow, Scotland, this 28th day 40 of April, 1897.

ANTHONY DIXON BROGAN.
ANDREW MURRAY MALLOCII.
